UNITED STATES PATENT OFFICE.

STERLING ELLIOTT, OF NEWTON, MASSACHUSETTS.

MACHINE FOR MAKING STENCIL-STRIPS.

1,140,889.

Specification of Letters Patent.

Patented May 25, 1915.

Original application filed May 11, 1912, Serial No. 696,606. Divided and this application filed May 19, 1913. Serial No. 768,450.

To all whom it may concern:

Be it known that I, STERLING ELLIOTT, a citizen of the United States, residing at Newton, in the county of Middlesex and State of Massachusetts, have invented an Improvement in Machines for Making Stencil-Strips, of which the following is a specification.

In Letters Patent #1,034,600, dated August 6, 1912, a stencil-strip is shown composed of paper from which paper stencils are cut. Said stencil-strip is composed of a strip of paper, termed the "blank-strip", placed between the folds of another strip of paper, termed the "frame-strip", the said strips being adhesively secured together. The folded frame-strip has holes cut in it, arranged in pairs, side by side, so that the holes of each pair register with each other when the strip is folded, and said folded strip is scored lengthwise between the holes of the successive pairs to define the line of fold and to cause the portions of the strip when folded to lie flat upon the blank-strip.

This invention relates to a machine adapted to produce the frame-strip, being automatic in operation; and involves many combinations of elements which are especially designed to perform the work intended for them.

The automatic machine here shown, for the purpose of illustrating my invention, comprises mechanism constructed and arranged to feed forward a strip of paper to form the frame-strip, and to cut holes in said strip, which holes are arranged in pairs, side by side, and at regular distances apart, and to score said strip continuously between the holes of successive pairs to enable the strip to be folded, whereupon the holes of each pair register with each other, thereby to form the frame-strip, and said mechanism is of a rotary character and adapted to move forward and cut the strip of paper by a continuous rotary motion of its parts. Automatic stopping and starting means are preferably provided for said feeding and cutting-mechanism which is controlled by the strip which is delivered therefrom, so that the length of strip which is cut and delivered may be regulated. Such form of mechanism is especially well adapted for this work, for the reason that it is very rapid

in operation, but my invention is not limited to the employment of this particular form of mechanism for forming the frame-strip.

The automatic mechanism here shown is hereby designed for use in connection with other automatic mechanism shown in my application #696,606, filed May 11, 1912, of which this application is a division, for the production of stencil-strips of the aforesaid application.

Figure 1 is a side elevation of strip feeding and cutting machine embodying this invention. Fig. 2 is an enlarged plan view of the feeding and cutting-mechanism for the frame-strip. Fig. 3 is an enlarged end view of the rolls constituting the feeding and cutting-mechanism for the frame-strip. Fig. 4 is a front elevation of the feeding and cutting rolls shown in Fig. 3. Fig. 5 is a transverse section of a pair of rolls employed to remove the pieces from the frame-strip which are cut by the cutting-roll. Fig. 6 is a front elevation of the rolls shown in Fig. 5. Fig. 7 is a plan view of a portion of the frame-strip.

Referring particularly to the machine as here illustrated, the strip 25 of paper, such as tag stock or some similar kind of paper, and of the desired width to form the frame-strip, is drawn from a roll 26, Fig. 1, over a plane-surfaced idle-roll 27, and then between horizontally arranged upper and under guide-plates 28, 29, by a pair of positively driven rolls 30, 33, (see Figs. 2, 3 and 4), which rolls are also constructed to cut the strip, thereby to form holes therein while feeding it forward. 30 represents the under-roll of the pair. It has a plane cylindrical surface and serves as a bed-roll on which the strip of paper is cut, as well as a feed-roll. It is journaled at its ends in bearing-blocks 31, of any suitable construction which are supported by the frame-work. It is positively driven, and as here shown, has secured to one of its journals a small toothed gear 32 for this purpose. 33 represents the upper-roll of the pair. It is formed as a cylinder and has on its cylindrical surface sharp-edged ribs 34, arranged in quadrangular form to cut the strip of paper so that quadrangular shaped pieces may be removed to form holes therein; and, as here shown, four such quadrangularly arranged ribs are

employed, which are arranged in two pairs, and designed to cut the strip to produce two pairs of holes during each rotation, the holes of each pair being side by side. It also has 5 on its cylindrical surface a sharp edged rib 35, which is extended circumferentially entirely around it, designed to score the strip of paper between the holes of each pair. It also has on its cylindrical surface narrow, plane-edged ribs 36, 36, to engage the strip of paper for the purpose of holding it in engagement with the roll 30, and to feed it forward, said ribs being arranged at opposite sides of the rib 35. It is journaled at 10 its ends in bearing-blocks 37, supported by the frame-work, and is positively driven, having secured to one of its journals a small toothed-gear 38, for this purpose, which is in mesh with the toothed-gear 32. 15 The bed-roll 30 is made of hardened steel, and it is designed and intended that the cutting ribs 34 on the cutting-roll shall terminate close to but free from contact with the surface of said bed-roll, so that the strip of 20 paper will be cut sufficiently to enable the quadrangularly shaped pieces to be subsequently removed by suitable means to be hereinafter described, but the rib 35 does not terminate quite as close to the surface of the 25 bed-roll, as it is only employed to score the strip. 30

The cutting ribs 34, 34, scoring-rib 35, and plane-edged feeding-ribs 36, 36, are very carefully and accurately formed, and means 35 are provided to adjust the roll 33, bearing them toward and from the bed-roll 30, to correctly position it with respect thereto.

Referring to Fig. 3, long screws 40, 40, extend through holes in the frame-work and 40 through holes in the upper part of each bearing-block 37, and through screw-threaded holes in the lower part of each bearing-block 37, and their ends engage the tops of the bearing-blocks 31, so that the bearing-blocks 45 37, are connected with and adapted to be moved by the turning of the screws and the position of the upper roll relative to the bed-roll thereby adjusted.

The strip 25, on leaving the cutting-rolls 50 30, 33, is fed forward to a pair of rolls, (see Figs. 5 and 6), which are constructed and arranged to remove from it the severed or substantially severed quadrangular pieces. As here shown 45 represents the upper-roll 55 of the pair. It is formed as a cylinder and journaled at its ends in suitable bearings, but is driven by gears with its fellow roll when the strip of paper is arranged between them. It has ribs 46 arranged on and extended partially around its cylindrical surface, arranged in pairs, there being two pairs on one side of the cylinder, arranged side by side, and two pairs on the other side of the cylinder, arranged side by side. Each pair 60 of ribs is made of a length and width corre-

sponding to the length and width of the quadrangular pieces which are to be removed from the strip, and of the holes, to be thereby produced. Fingers 47 are arranged above the roll which engage tangentially the cylindrical surface of the roll at the sides of the ribs, and which act to prevent the strip from winding on the roll in case it should have a tendency to do so. 48 represents the under-roll of the pair. It is 70 formed as a cylinder and is journaled at its ends in bearings, and is positively driven, having secured to one of its journals a small toothed gear 49 for this purpose. It has several circumferential grooves, as 50, arranged opposite the ribs 46, to receive said ribs and thereby to enable them to extend below the meeting plane of the two rolls, so as to exert a downward pressure upon the portions of the strip to be removed, and to 80 detach them from the strip. It has also circumferential grooves, as 51, at the bottoms of the grooves 50, arranged opposite the spaces between the ribs 46, which admit of the employment of fingers 52, arranged 85 tangentially to its cylindrical surface, which prevent winding of the pieces on the roll in case they should have a tendency to do so. Its plane or ungrooved portions are in parallel with and adapted to cooperate with the 90 portions of the roll 45, at the sides of the ribs 46, to engage and feed the strip forward. As the circumference of the ribbed portions of the upper-roll is greater than the circumferences of the grooved portions of the under-roll, it will be seen that when the ribs 46 engage the quadrangular pieces which are to be removed from the strip and they act to 95 depress them with relation to the strip, and as represented in Fig. 7, they also act to 100 advance the detached pieces at a greater rate of speed than the strip is being moved, so that the forward ends of said pieces will be projected beyond the corresponding ends of the holes, which is an advantage. Individual driving-means is herein provided for 105 this group of mechanism, which is adapted to be automatically started and stopped according to the amount of strip which is required, and herein an electric-motor 55 is 110 employed as a driving-means, its shaft bearing a pinion 56, which engages a large toothed gear 57, secured to a shaft bearing a small toothed gear 58, which engages a large toothed gear 59, secured to one of the journals of the cutting-roll 33, thereby to rotate 115 said roll; and the toothed gear 38 on the other journal of said cutting roll being in mesh with the toothed gear 32, on the bed-roll operates to rotate said bed-roll; and said 120 toothed gear 32 engages a large toothed gear 60, which in turn engages the small toothed gear 49, on the grooved under-roll 48, thereby to rotate said under-roll. As the motor-shaft is rotated the several rolls are rotated 125 130

and the strip is continuously fed along and cut and the pieces detached from it. The detached pieces 62, represented by dotted lines Fig. 1, are permitted to fall by gravity 5 down a suitable chute, and the perforated strip 25 is carried along over an idle-roll 63, thence under a gravitating take-up 64. As a means to automatically start and stop this group of mechanism, the motor is controlled, 10 and, as here shown, the switch-arm 65 of any suitable electric-switch which controls the circuit of the motor is connected by a link 66, with a pivoted counterbalanced arm or frame 67, bearing the take-up roll 64, so that 15 as the take-up roll is raised and lowered by the strip its arm or frame 67, will be moved on its pivot and the switch-arm operated. When more strip is being delivered than is required, the take-up roll falls by gravity 20 and the switch-arm is moved to open the circuit of the motor, thereby to stop this group of mechanism. As the take-up roll rises the switch-arm is moved in the opposite direction to close the circuit of the motor, there- 25 by to start this group of mechanism.

I claim:—

1. In a machine for making frame-strips for stencils, the combination of a plane-surfaced bed-roll and a roll having on its surface cutting-ribs, feeding-ribs and a scoring-rib, the engaging portions of said ribs terminating in different planes with respect to the surface of the bed-roll, said feeding-ribs and scoring-rib extending entirely 30 around the roll, said rolls coöperating to feed forward a strip of paper and cut holes therein and score it longitudinally, means to rotate said rolls, and means to remove the 35

cut pieces from the strip, substantially as described. 40

2. In a machine for making frame-strips for stencils, the combination of rotary strip-cutting means for the frame-strip, a ribbed-surfaced roll and a grooved-surfaced roll, arranged in parallel relation with said strip-cutting means, said rolls coöperating to remove the cut pieces from the strip while the strip passes between them, and means to rotate said rolls, substantially as described. 45

3. In a machine for making frame-strips for stencils, the combination of rotary means to feed forward and cut holes in a strip of paper to form the frame-strip, electric-driving-mechanism for said means including an electric-motor, a switch for the circuit 50 of said motor, and means arranged to automatically operate said switch to start and stop the motor, substantially as described. 55

4. In a machine for making frame-strips for stencils, the combination of rotary means to feed forward and cut holes in a strip of paper to form the frame-strip, electric-driving-mechanism for said means including an electric-motor, a switch for the circuit of 60 said motor, a take-up roll for the strip, the position of which is controlled by the strip, and means connecting said take-up roll with said switch, substantially as described. 65

In testimony whereof, I have signed my name to this specification in the presence of 70 two subscribing witnesses.
